UNITED STATES PATENT OFFICE.

WILHELM ZWILLING, OF GEISSEN, GERMANY.

METHOD OF SECURING STAY BOLTS AND THE LIKE.

1,404,561.

Specification of Letters Patent. Patented Jan. 24, 1922.

Original application filed November 28, 1919, Serial No. 341,311. Divided and this application filed February 5, 1921. Serial No. 442,877.

To all whom it may concern:

Be it known that I, WILHELM ZWILLING, a citizen of Germany, residing at Geissen, Germany, have invented certain new and 5 useful Improvements in Methods of Securing Stay Bolts and the like, (for which I have filed application in Germany Sept. 17, 1918; in France Aug. 13, 1919; in Italy Aug. 14, 1919; in Belgium Aug. 14, 1919; in Sweden Aug. 20, 1919; in Denmark Aug. 9, 1919; in Holland Aug. 25, 1919; in Austria Aug. 2, 1919; in Hungary Aug. 9, 1919; in Great Britain Aug. 12, 1919, and in Switzerland Mch. 18, 1919, Patent No. 82816,) of which 10 the following is a specification.

The present invention relates to stay-bolts and the like, and is a division of my co-pending application on stay-bolts, filed November 28, 1919, Serial No. 341,311. It has 20 for its object to provide an improved method of securing a stay-bolt in its seat so that no leakage will result at the joint even when subjected to high pressure, as is the case, for instance, when the bolt is used in a steam 25 boiler.

Various expedients have been tried for accomplishing this result; for instance a hollow tube having external screw threads at an end has been used for the bolt, into the 30 ends of which is forced a tapered or conical-shaped die for the purpose of spreading out the end of the tube and forcing the threads on it into intimate contact with the threads in the seat. This method, however, has not 35 given satisfactory results for the reason that when the conical-shaped die is forced into the end of the bolt the die exerts its greatest pressure and spreading effect at the outer or thickened end, while the inner or narrow 40 end of the die exerts comparatively little pressure and spreading effect. Thus after the bolt has been seated in this manner the screw-threads on the bolt are forced intimately into contact with the screw-threaded 45 seat at points near the mouth of the cavity and this intimate contact is maintained for only a relatively small axial distance.

To overcome this defect I have devised a 50 method of spreading stay-bolts in their seats, in which the threaded end of the stay-bolt is provided with a longitudinally extending substantially cylindrical cavity into which at least one die having a substantially cylindrical active portion of a diameter greater 55 than the diameter of the cavity is forced, so

that the screw-threaded end of the bolt along its length is forced uniformly into intimate contact with the screw-threaded seat. By this method the pressure from the die is exerted outwards radially at substantially 60 right angles to the cylindrical wall of the cavity, and the wall is expanded outwardly to the same extent along the full length of the expanded portion. In the case of the tapered die the pressure is exerted diagonally 65 to the cylindrical walls of the cavity, and the wall is expanded outwardly to an extent which diminishes from the mouth of the cavity inwards. I prefer, instead of using only one die, to use a plurality of dies 70 in succession, the diameter of each die being greater than that of the cavity, and each succeeding die being of greater diameter than the preceding one. In this manner the bolt end is spread more gradually and therefore 75 with less chance of injury, and a highly effective leak-proof joint is secured, since the greatest number of threads are brought into intimate contact.

The accompanying drawings illustrate the 80 form of stay-bolt covered in my copending application, Serial No. 341,311, above referred to; and I will now describe my method as employed in connection with same.

In said drawings, Figure 1 is a central 85 longitudinal section through a stay-bolt and a portion of the wall in which it is seated, and

Figure 2 is a similar view showing the die for spreading the bolt into its seat, together 90 with the means for withdrawing the die.

Referring more specifically to said drawings, *a* and *b* are the boiler or other walls to be braced by the stay-bolt *c*; and *d d* are the screw-threaded ends of the bolt *c*, which 95 ends I provide with the substantially cylindrical longitudinally extending cavities *e e*. The cavities are usually, but not necessarily, connected by means of the boring or tell-tale hole *h*. The invention is equally applicable 100 to a bolt not provided with a tell-tale hole, since the latter forms no part of the present invention. The ends *d d* of the bolt are represented as of larger diameter than the main body *c*; this is done in order that a sufficiently large cavity may be provided. The 105 first step in my method is the provision of the cylindrical cavity or cavities in the end or ends of the bolt.

After the bolt has been screwed into its 110

seat in the wall b , a die i having a substantially cylindrical active portion of suitable size, and having a diameter greater than the diameter of cavity e , is driven into the cavity by means of a hammer, hydraulic press or the like, thus forcing the walls of cavity e outwards. This action presses the screw-threads on end d into intimate contact with the screw-threaded seat in wall b .
10 The die i is then removed, a die of slightly greater size is driven in and removed, and so on, until the screwthreads have been forced into the most effective intimate contact. The work is then completed. The annular flange n is formed on the die to prevent the latter from being driven too far into the cavity.

To facilitate the removal of the die from the cavity I provide it with a threaded ring m which is fitted over it and is held in position by a cotter k , which latter is passed through the die and serves as an abutment for the ring. A nut l , provided with internal screw threads, is adapted to be screwed on to the ring m , and when it is screwed down to abut against the wall a it withdraws the die i from the cavity.

It will be noted that according to my method, the spreading force is exerted radially upon the cylindrical wall of the cavity in a direction at right angles to the wall, so that the wall is expanded outwardly to the same extent along the full length of the expanded portion, and that this spreading or expansion is equally distributed along the length of the seat so that all the threads on the seat are brought into intimate contact with the threads on the bolt.

I claim:

40 1. The method of securing a stay-bolt having an end provided with external

screw-threads, which comprises providing a cylindrical cavity in said end, screwing the bolt into its seat in a structure to be braced by it, and then repeatedly widening said cavity by internal pressure exerted outwards radially at right angles to and along the cylindrical wall of the cavity. 45

2. The method of securing a stay-bolt having an end provided with external screw-threads, which comprise providing a cylindrical cavity in said end, screwing the bolt into its seat in a structure to be braced by it, and then repeatedly exerting pressure in said cavity to expand the wall thereof outwardly to the same extent along the full length of the expanded portion. 50 55

3. The method of securing a stay-bolt having an end provided with external screw-threads, which comprises providing a cylindrical cavity in said end, screwing the bolt into its seat in a structure to be braced by it, widening said cavity by forcing therein at least one die having a cylindrical active portion of a diameter greater than the diameter of said cavity, and then withdrawing the die. 60 65

4. The method of securing a stay-bolt having an end provided with external screw-threads, which comprises providing a cylindrical cavity in said end, screwing the bolt into its seat in a structure to be braced by it, and then repeatedly widening said cavity by successively forcing therein a plurality of dies each having a cylindrical active portion of a diameter greater than the diameter of said cavity and each successive die having a cylindrical active portion of gradually increasing diameter with respect to that of the preceding die. 70 75

WILHELM ZWILLING.
